UNITED STATES PATENT OFFICE

164,278

BUILDING

Rowell A. Billups and Guy C. Billups, Greenwood, Miss., and William L. Billups, New Orleans, La., assignors to Billups Petroleum Co., Greenwood, Miss., a corporation of Mississippi

Application December 5, 1950, Serial No. 13,280

Term of patent 14 years

(Cl. D13—1)

To all whom it may concern:

Be it known that we, Rowell A. Billups, Guy C. Billups, and William L. Billups, citizens of the United States, residing at Greenwood, Greenwood, and New Orleans, respectively, in the counties of Leflore, Leflore, and in the parish of Orleans, respectively, and in the State of Mississippi, Mississippi, and Louisiana, respectively, have invented a new, original, and ornamental Design for a Building, of which the following is a specification, reference being had to the accompanying drawing, forming part thereof.

The figure is a perspective view of a building showing our new design.

The essential features of the design are shown in full lines.

The back of the building is plain.

We claim:

The ornamental design for a building, as shown and described.

ROWEll A. BILLUPS.
GUY C. BILLUPS.
WILLIAM L. BILLUPS.
